UNITED STATES PATENT OFFICE.

BARNEY R. NYHAGEN, OF NEW YORK, N. Y.

ENGINE-VALVE.

1,330,649.

Specification of Letters Patent. Patented Feb. 10, 1920.

Application filed August 25, 1917, Serial No. 188,250. Renewed February 28, 1919. Serial No. 279,889.

To all whom it may concern:

Be it known that I, BARNEY R. NYHAGEN, a citizen of the United States, residing at New York city, in the county of New York and State of New York, have invented new and useful Improvements in Engine-Valves, of which the following is a specification.

This invention relates to engine valves and is in the nature of an improvement upon 10 and modification of the valve structure set forth in my original application filed April 14, 1917, Serial No. 162,104 and renewal application filed Feb. 28, 1919, and bearing Serial No. 279,888, and patented Oct. 7th, 15 1919, and bearing the Patent Number 1,318,227.

One of the chief objects of the present invention is to produce a valve structure which will admit of a comparatively free 20 and unresisted movement of the fresh and burned charges to and from the combustion chamber of the cylinder of the engine in connection with which the valve is employed.

25 A further object of the invention is to produce a valve structure which is capable of being used in conjunction with one or more cylinders, enabling a single valve to take care of the fresh charges admitted to one 30 cylinder or to adjacent cylinders and also take care of the exhaust of the burned gases therefrom.

With the above and other objects in view, the invention consists in the novel construction, combination and arrangement of parts, herein fully described, illustrated and claimed.

In the accompanying drawings:

Figure 1 is a horizontal section taken 40 through adjacent cylinders of an engine and also through the valve structure, said section being taken in line with the inlet and exhaust ports of the cylinders.

Fig. 2 is a vertical section on the line 45 2-2 of Fig. 1 showing the left hand piston at the beginning of the suction stroke and the right hand piston at the beginning of the power stroke.

Fig. 3 is a similar view showing the left 50 hand piston at the beginning of the compression stroke and the right hand piston at the beginning of the exhaust stroke.

Fig. 4 is a similar section showing the left hand piston at the beginning of the ex-

plosion or working stroke and the piston of 55 the right hand cylinder at the beginning of the suction stroke.

Fig. 5 is a similar view showing the left hand piston at the beginning of the exhaust stroke and the right hand piston at the beginning of the compression stroke, and 60

Fig. 6 is a vertical section taken at a right angle to Figs. 2, 3, 4 and 5.

Referring primarily to Fig. 1, A and B designate adjacent cylinders in which are 65 mounted the reciprocating pistons *a* and *b*, the cylinders A and B being inclosed by a water jacket *c*.

In the preferred embodiment of the invention, a substantially cylindrical valve casting or chamber 1 is cast integrally with the cylinders A and B and communicates by means of ports 2 and 3 with the cylinders A and B, respectively. The casing 1 also communicates with the cylinders A and B 75 by other ports 4 and 5 arranged at a lower point. 5^a designates an intake pipe or manifold which may have as many branches as necessary in accordance with the number of cylinders employed, 6 designating one 80 branch of the manifold 5 which communicates with an intake port 7 leading into the valve casing 1. Arranged below the intake manifold 5 is a similarly formed exhaust manifold, a branch of which leads to an exhaust port 8 of the valve casing 1. Each of the manifolds comprises a pipe 9. The head portion of the manifold is shown as cast integrally with the cylinder block, the pipe 9 being formed separately therefrom and having a flange 10 which is secured to the manifold head by fastening means 11.

The valve structure comprises an outer sleeve-like member C and an inner sleeve-like member D.

The inner valve member D is of hollow formation and generally cylindrical in shape, being closed at its upper end by a head 12 and at its lower end by a head 13, the latter being inclined as shown to provide an underlying space 14 in which is located the pivot pin 15 which connects the upper extremity of one of the valve operating rods 16 to the respective valve member, said rod being connected to the crank of an 100 underlying crank shaft (not shown) which controls the movements of the valve member. Another connecting rod 17 extends

from said crank shaft to the outer valve member C to which it is connected by a pivot 18.

Extending diametrically through the 5 valve member D is an inclined intake passage 19 terminating in the ports 20 and 21. Intersecting the intake passage 19 is a branch passage 22 (see Fig. 6) terminating in a port 23. The passages 19 and 22 are 10 cut off from the remainder of the interior of the valve member D thereby leaving an exhaust receiving space comprising the upper and lower portions 24 and 25 and the intermediate connecting portion 26 which 15 lies at one side of the branch intake passage 22. The valve member D is further provided with an upper exhaust port 27 at one side and another exhaust port 28 at the opposite side and lower than the port 27, 20 the latter being located at a lower level than the exhaust port 28. The valve member D is further provided with auxiliary exhaust ports 30 and 31 arranged near the lower end thereof and at diametrically opposite points, 25 the port 30 being located at a higher elevation than the port 31.

The outer valve member C is of true cylindrical formation and open at both ends. Said outer valve member comprises an intake port 32 near the upper end thereof and is formed in the opposite wall thereof with another intake port 33 located at a lower point than the port 32. Said valve member C is also formed with an exhaust port 34 30 in one side thereof, and is formed in the opposite side thereof with an exhaust port 35 arranged about on the same level as the port 34. The cranks of the shaft to which the rods 16 and 17 are connected are offset approximately 90° from each other. The cycles of operation in one cylinder are followed by the corresponding cycles of operation in the adjacent cylinder. For example, referring to Fig. 2, the valve members C and D have reached a position where the left hand piston a is at the beginning of its suction stroke while the left hand piston b is at the beginning of its power stroke. At 40 this time the valve members C and D are both moving upwardly but the valve member D is traveling faster than the valve member C, the connecting rod 17 being at or near its lowest center while the connecting rod 16 is on the quarter and therefore at its maximum rate of movement. In Fig. 3 the left hand piston a is at the beginning of its compression stroke while the piston b is at the beginning of its exhaust stroke, the valve member C is moving upwardly at nearly its 45 maximum while the member D is nearly at the upper limit of its movement and is therefore moving very slowly or is practically at rest.

In Fig. 4 the left hand piston a is at the 65 beginning of its explosion or working stroke

while the piston b is at the beginning of its suction stroke. At this time the valve member D is moving upwardly at its maximum speed while the member C is practically on center or nearly stationary. In Fig. 5 the 70 left hand piston a is at the beginning of its exhaust stroke while the right hand piston b is at the beginning of its compression stroke. At this time the valve member D is nearly stationary, while the valve member C is 75 moving downwardly at approximately its maximum speed.

From the foregoing description taken in connection with the accompanying drawings, it will now be understood that by reason of the valve structure employing the two telescopically related and interfitting valve members, and the manner in which they are operated, one of the adjacent pistons is operating two strokes ahead and behind the 80 piston of the other cylinder. In a four cylinder engine embodying the improved valve mechanism, the cycles follow each other in the four cylinders, one cylinder intaking while another cylinder is firing, another exhausting, and the remaining cylinder compressing. This produces a nicely balanced engine and only two valves are required for the four cylinders. In the case of a two cylinder engine, only one valve is 90 necessary.

I claim:

1. The combination of a cylinder having a single combined intake and exhaust port communicating with the head of the combustion chamber thereof, a valve, a valve casing for said valve having a port in constant register with said cylinder, port, and also having an exhaust port, said valve comprising two reciprocatory hollow and substantially cylindrical members working telescopically one within the other, and means for reciprocating said valve members out of unison so that when one of said valve members is at rest or nearly so, the other valve member is traveling at its maximum speed or nearly so, said valve members having ports in their side walls adapted to register with each other and with said cylinder port, and the valve casing inlet and exhaust ports, the inner valve member comprising an inclosed intake passage extending diametrically therethrough, and also having a ported exhaust space surrounding said intake passage.

2. The combination of adjacently located cylinders, a valve common to said cylinders, a valve casing for said valve having a port leading to each cylinder and acting both as an intake and an exhaust port, an intake port leading to said valve casing, and an exhaust port leading from said valve casing, said valve comprising two hollow and substantially cylindrical members working telescopically one within the other, and means 125

120

125

130

for reciprocating said valve members out of unison so that when one of said valve members is at rest or nearly so, the other valve member is traveling at its maximum speed or nearly 5 so, said valve members having ports in their side walls adapted to register with each other and with the cylinder port and the valve casing intake and exhaust ports, the inner valve member comprising an inclosed 10 intake passage extending diametrically and at an inclination therethrough.

3. The combination of adjacently located cylinders, a valve common to said cylinders, a valve casing for said valve having a port 15 leading to each cylinder and acting both as an intake and an exhaust port, an intake port leading to said valve casing, and an exhaust port leading from said valve casing, said valve comprising two hollow and sub- 20 stantially cylindrical members working telescopicly one within the other, and means for reciprocating said valve members out of unison so that when one of said valve members is at rest or nearly so, the other 25 member is traveling at its maximum speed or nearly so, said valve members having ports in their side walls adapted to register with each other and with the cylinder port and the valve casing intake and exhaust 30 ports, the inner valve member comprising an inclosed intake passage extending diametrically and at an inclination therethrough, and also comprising a second intake port and a branch passage connect- 35 ing the last named port with said inclined intake passage.

4. The combination of adjacently located cylinders, a valve common to said cylinders, a valve casing for said valve having a port

leading to each cylinder and acting both as 40 an intake and an exhaust port, an intake port leading to said valve casing, and an exhaust port leading from said valve casing, said valve comprising two hollow and sub- 45 stantially cylindrical members working telescopicly one within the other, and means for reciprocating said valve members out of unison, so that when one of said valve members is at rest or nearly so, the other valve member is traveling at its maximum speed 50 or nearly so, said valve members having ports in their side walls adapted to register with each other and with the cylinder port and the valve casing intake and exhaust ports, said valve members being further pro- 55 vided with auxiliary exhaust ports and the cylinders being provided with corresponding auxiliary exhaust ports, the said exhaust ports of the valve members and the cylinders being arranged to register with 60 each other when the pistons are near the lowest limit of their movement.

5 In an internal combustion engine, the combination of a cylinder having a single port communicating with the combustion 65 chamber thereof and acting both as an intake port and an exhaust port, a valve comprising two reciprocating hollow and substan- 70 tially cylindrical members working telescopicly one within the other and means for reciprocating said valve members out of unison, the inner valve member comprising an inclosed intake passage extending dia- 75 metrically therethrough and a ported exhaust space surrounding said intake passage.

In testimony whereof I affix my signature.

BARNEY R. NYHAGEN.
